UNITED STATES PATENT OFFICE

TRACY W. SIMPSON, OF BERKELEY, CALIFORNIA

WINDOW LIGHT AND ILLUMINATED SIGN

Application filed January 16, 1928, Serial No. 247,067. Renewed December 4, 1929.

This invention has to do with certain improvements in lighting fixtures and the like; and has reference particularly to improvements in window foot lights, etc., such as are used for illumination of store windows. The invention relates to improvements in the arrangement of the reflectors as well as means whereby the same lamps which supply illumination for the interior of the window cabinet also provide the illumination for signs or announcements displayed through the windows.

One object of the invention is to so relate the reflector, the sign face and the light source, that the latter will do double duty, providing the illumination necessary for lighting the interior of the cabinet as well as illuminating the sign face. This result is accomplished by an arrangement whereby the source of light is placed on the reflecting side of the reflector (preferably at the reflecting center), the reflector being provided with an opening through which a portion of the light from said source passes directly backwards through the reflector to the sign face. The arrangement is also such that the amount of backward illumination through said opening is sufficient to illuminate the sign face more or less uniformly over its entire area.

More particularly, the arrangement is one in which the lamp socket for the incandescent lamp is placed intermediate between the reflector and the sign face, the incandescent lamp extending through the reflector opening into said socket, but the illuminating center of the lamp or source of light being on the reflecting side of the reflector. The opening in the reflector thus performs double duty in the sense that it accommodates the lamp which extends through it into the socket, and in the further sense that it passes the necessary illumination for the sign face.

Said opening is also made of such a size, shape and position that the line of cut off for the backward illumination does not interfere with a complete illumination of the entire sign face.

A further feature of the invention is to provide a cylindrical reflector which is pro-

vided with a reflecting surface in the form of ribs lying in planes more or less normal to the axis of the reflector itself, said reflecting surfaces being arranged on such angles that the light from the source is reflected into the window cabinet substantially normal to the axis of the reflector. This will greatly reduce the side spread of illumination and will improve the combined effect produced by the entire structure.

A further object of the invention is to provide a combined structure performing all the foregoing results in a very compact arrangement, and it is also an object to greatly reduce the bulk of the structure so that it can be advantageously used in show windows where space is of prime importance.

Other objects and uses of the invention will appear from a detailed description of the same which consists in the features of construction and combination of parts hereinafter described and claimed.

In the drawings:

Figure 1 shows a face view of a foot light unit embodying the features of the present invention and looking towards the display face of the sign, the central portion of the unit being broken away so as to shorten up the figure.

Fig. 2 shows a view corresponding to Fig. 1 but looking at the other side of the structure, namely, the reflecting side, as seen from the interior of the window cabinet;

Fig. 3 shows a cross section through the unit taken on the line 3—3 of Fig. 2 looking in the direction of the arrows but on an enlarged scale;

Fig. 4 shows an end view at one end of the casing, on a scale larger than that of Fig. 2 and smaller than that of Fig. 3;

Fig. 5 shows a perspective of a portion of a reflecting surface embodying the features of the present invention; and

Fig. 6 shows a fragmentary longitudinal section through a portion of the reflector together with a pair of adjacent lamps, and said figure shows the general form and relationship of the reflecting ribs as compared to the light sources so as to secure normal reflection.

Briefly stated the arrangement includes a trough shaped or generally cylindrical reflector 10 the concave surface of which faces into the window cabinet so as to throw the 5 major portion of the illumination into said cabinet.

Said channel shaped reflector is provided with one or more lamp openings 11; and the incandescent bulbs 12 are extended through 10 said openings so that their stem portions 13 may be threaded into suitable lamp sockets 14 on the convex side of the reflector. Said 15 sockets 14 are placed at such positions that the illuminating centers 15 of the respective lamps lie on the concave side of the reflecting unit, and substantially on the reflecting axis of the cylindrical reflector.

The openings 11 will allow a portion of the illumination from the illuminating centers 15 to pass backwardly; and by properly shaping 20 the openings 11 with respect to the positions of the illuminating centers and lamp sockets it is possible to largely control and predetermine the effect of the backward illumination. Preferably the openings 11 are so placed with 25 respect to the sockets, and the lamps 12 are of such form, that more illumination is transmitted backwardly above the lamp axis than below said lamp axis as will be readily apparent from Fig. 3.

Behind the convex reflector and beyond the positions of the sockets 14 there is placed a sign face 16, of transparent or translucent material. The same may be of suitable form 35 such as a transparent or translucent glass plate having opaque raised letters applied thereto. This sign face is illuminated by backwardly traveling rays from the center of illumination passing through the opening 11, most of said rays passing above the lamp 40 socket 14 and the base portion of the lamp itself. This is clearly evident from the lines 17 and 18 which more or less define the upper and lower limits of illumination necessary 45 for the sign face.

Ordinarily the foot light unit will be of substantial length as compared to its other dimension, in which case there will be provided a number of the openings 11 together 50 with lamp sockets and lamps corresponding thereto. The openings 11 will in such case be elongated laterally as shown in Fig. 6 at 19 and 20, a sufficient amount to allow the backward illumination to spread sidewise sufficiently to give a substantially uniform 55 illumination throughout the entire length of the sign face. This result may be readily accomplished without unduly interfering with the reflection of light forwardly into the cabinet, due to the presence of the reflecting ribs which I will now explain.

Intermediate between the lamp openings 11 there are formed in the reflector a series of vertical or cross wise ribs 21 best shown in Fig. 6. These ribs are provided with the re-

flecting surfaces 22, 23, 24, 25 and 26 which said surfaces are formed on conical angles such that the illumination striking them is reflected straight out into the body of the cabinet, so that all the reflection is performed 70 in a substantially parallel manner as indicated by the rays 27 in Fig. 6. These reflecting surfaces in other words are so formed as to take account of the principle that the angle of incidence is always equal to the angle of reflection. 75

Thus I have provided not only an arrangement which accomplishes the illumination of the sign face at the back side of the structure, but which also gives a substantially uniform 80 illumination of said sign face, together with a substantially normal reflection of all of the reflected light which is thrown into the cabinet from the concave reflecting surface.

As a matter of convenience in construction 85 the elements already referred to may be assembled into the structure which I will now explain in detail.

The same includes a box like housing combining a pair of end sheets of generally trapezoidal form such as 28 in Figs. 3 and 4. The lower forward portion of the housing is established by a sheet 29 which is folded into a generally angular form, the upper edge thereof being refolded downwardly and then inwardly at 30 to establish a lip 31. The lower edge of the sheet 29 is preferably off set upwardly as shown at 32 to accommodate the thickness of a bottom plate 33. 90

The ends of the sheet 29 are folded upwardly and inwardly as shown at 34 and 35 and are provided with ears 36 and 37 which are extended through slots in the end walls 28 so as to join the parts together. 100

Likewise, there is another sheet 38 which is formed to establish a top or roof 39, together with a bottom portion 40, the inner edge of the latter being offset upwardly at 41 to accommodate the thickness of a bottom sheet. 105

The central portion of the sheet 38 is pressed or drawn inwardly in a suitable fanciful design as shown at 42 and is provided with a rectangular opening 43 through which the sign face 16 is displayed. The sheet 38 also has its end portions folded downwardly and upwardly as shown at 44 and provided with ears 45 which extend through slots in the end plates 28 so as to join the parts together. 115

The various lamp sockets 14 are supported by a bracket 46 which comprises a sheet metal plate folded into the desired form and having the feet portions 47 and 48 by means of which it is mounted upon the base flanges upturned at 32 and 41 as already referred to. The base plate 33 sets up into the upset portions 32 and 41, and machine screws 49 are passed through the plate 33 and other parts so as to join them together. 120

The plate 46 comprising the support for the various sockets 14 has its end portions closed by end sections 50 which are secured to it and are provided with suitable openings 51 for the accommodation of conduits or other electrical conductor carriers. Preferably also the end plates 28 already referred to are provided with curved openings 52 in line with the end plates 50 of the socket unit, 10 and said end plates 28 may be rounded downwardly to said openings 52 as shown in 53 in Fig. 4.

Afterwards there may also be provided a stiffener plate 54 within the structure, the 15 same being provided with a top flange 55 which rests against the roof 39 already referred to; and said stiffener plate is provided with a large central opening of sufficient height and length to pass all of the illumination 20 from the various lamps necessary for the sign face 16.

If desired also another stiffener plate 56 may be provided in the lower portion of the structure, the same being secured to the flange 25 31 and having its lower edge resting upon the base portion 48 of the socket support.

The reflector 10 is conveniently set into place and supported by having its lower edge rest upon the flange 30 already referred to, 30 and by having its upper edge leaning backwardly against the upper portion of the stiffening plate 54. In such case the plate 29 should be provided with an upstanding ledge or ear 57 (see Fig. 3) which will support the 35 lower edge of the reflector 10 and prevent it from sliding forwardly away from the rest of the structure.

When the foregoing arrangement is used the clearance between the ledge 57 and the 40 front edge of the roof 39 should be such as to allow the reflector to be conveniently withdrawn from the structure after the lamps 12 have been unscrewed from their respective sockets.

The reflector 10 itself is conveniently made 45 of a sheet of steel or other suitable material rolled into the desired form together with its ribs, and afterwards polished and suitably plated to give the reflecting surface.

The sign face 16 is held in place in any convenient manner, as by means of a series of 50 clips 58 on the back face of the sheet 38 properly positioned with respect to the opening 43.

While I have herein shown and described 55 only a single embodiment of the features of my present invention, still I do not intend to limit myself thereto except as I may do so in the claims.

I claim:

1. A window foot light comprising in combination a curved reflector, a translucent sign screen located opposite to the convex side of said reflector, there being a series of lamp 60 openings located in line lengthwise of the

reflector, a lamp socket on the convex side of the reflector opposite to each of said openings and intermediate between the reflector and the sign screen, an incandescent lamp extending through each of said openings and into the corresponding socket and having its center of illumination located substantially on the reflecting axis of the reflector, and a series of transverse reflecting ribs on the concave side of the reflector at each side of each lamp opening, said ribs having their reflecting surfaces so formed that the rays of light incident from the corresponding illuminating center are reflected substantially normal to the axis of the reflector, and the lamp openings being so formed with respect to the sockets, illuminating centers, and sign surface that backward illumination from the lamps pass through said openings for direct illumination of the sign surface substantially as described. 70 75 80 85

2. A window foot light comprising in combination a curved reflector having a series of lamp openings located along its central portion, means for supporting said reflector with its concave surface facing upwardly and in one direction, a series of lamp sockets at the convex side of the reflector and opposite to said openings, incandescent lamps extending through the openings and into the sockets, the parts being so positioned and related that the illuminating centers of the lamps lie substantially on the axis of the reflector, and so that openings of substantial size are left between the lamps and the upper portions of the respective openings for the passage of backward illumination, together with a sign screen located behind the position of the reflector and sockets and in position to receive the direct backward illumination aforesaid, and means for supporting the sign screen in such position substantially as described. 90 95 100 105

3. A window foot light comprising in combination a curved reflector having a series of openings located in alignment throughout its length, illuminating centers at the concave side of said reflector and opposite to said openings, means for supporting said illuminating centers in such positions, a series of transverse ribs in the reflector intermediate between said openings, said ribs being provided with reflecting surfaces of such position and angle as to receive rays of light incident from the illuminating centers and reflect said rays away from the concave surface of the reflector in paths substantially normal to the axis of the reflector, together with a sign screen adjacent to the convex side of the reflector and in line with the reflector openings and adapted to receive direct illumination from the illuminating centers passing through said openings substantially as described. 110 115 120 125
